(57) **CLAIM**

The ornamental design for a ceiling fan motor housing, as shown and described.

DESCRIPTION

FIG. 1 is a perspective view of a ceiling fan motor housing shown in use.

FIG. 2 is an enlarged side view of a motor housing in accordance with the present invention;

FIG. 3 is an enlarged perspective view of the motor housing in accordance with the present invention; and,

FIG. 4 is an enlarged bottom view of the motor housing in accordance with the present invention.

The broken line showing of the canopy, support rod, ceiling fan blades, blade irons, pull cords, circular top central portion, circular bottom central portion and light fixture is included for the purpose of illustrating environmental structure and forms no part of the claimed design.

1 Claim, 4 Drawing Sheets
